UNITED STATES PATENT OFFICE.

JULIUS K. LUX, OF WASHINGTON, DISTRICT OF COLUMBIA.

CIRCUIT-CONTROLLING DEVICE.

970,523.

Specification of Letters Patent. Patented Sept. 20, 1910.

Application filed February 12, 1907. Serial No. 357,043.

To all whom it may concern:

Be it known that I, JULIUS K. LUX, a citizen of the United States, residing at Washington, District of Columbia, have invented certain new and useful Improvements in Circuit-Controlling Devices, of which the following is a specification.

This invention relates to circuit controlling devices, and objects of the invention are to provide an improved means for mounting the movable contact of (rotary snap) switches whereby a more durable, inexpensive and simple construction is secured; to provide an improved means for connecting the detent-stop carrying-member of a rotary snap switch to its insulating base, whereby the breaking or cracking of the latter, due to impact on said member, will be prevented; to provide an improved means for mounting the contact portion of a switch terminal, whereby the contact portion will adjust itself to the contact which engages therewith; to provide a rubbing contact surface which will practically eliminate all wear of the contact engaging therewith; to provide an improved means for securing the contact members to the terminal post, whereby said members will be pressed toward each other; to provide an improved terminal post which will secure proper alinement of the contacts; to provide an improved means for securing the spindle engaging nut in the insulating handle; and to provide an improved indicating means, whereby a cheaper, simpler and more effective construction is secured.

With these and other objects in view the invention consists of the parts and combinations of parts hereinafter described, illustrated in the accompanying drawings and more particularly pointed out in the appended claims.

Referring to the accompanying drawings which form a part of this specification,— Figure 1 is a top plan view of a rotary snap switch embodying the principles of my invention; the handle and cover being removed; and showing the base partly broken away. Fig. 2 is a side view of the device shown in Fig. 1, and showing the cover, the handle and indicating means in position, partly broken away and partly in section to more clearly show the construction. Fig. 3 is a top plan view of parts of the device, showing the cover, the handle, the movable and fixed means for indicating the condition of the circuit, the luminous indication

(“On”) being exposed to view. Fig. 4 is a top view of another embodiment showing the indicating characters stationary. Fig. 5 is a detail perspective view of the shutter shown in Fig. 4. Fig. 6 is a sectional view of the embodiment shown in Figs. 4 and 5. Fig. 7 is a detail perspective view of the washer under the operating handle. Fig. 8 is a sectional view showing the means for securing the indicator guard to the cover of the device. Fig. 9 is a top view of the movable contact carrier. Fig. 10 is a bottom view of the insulation of the handle, showing how the handle is molded. Fig. 11 shows side and edge views of the plate that is fitted in the insulation shown in Fig. 10. Fig. 12 is a perspective view of the plate carried by the upper end of the nut. Fig. 13 is a sectional view of the nut. Fig. 14 is a side view of the handle spring. Fig. 15 is a perspective view of one of the detent operating cams. Fig. 16 is a perspective view of the upper end of one of the terminal posts. Fig. 17 is a perspective view of the contact fastening means. Fig. 18 is a perspective view of the detent-stop carrying-member. Fig. 19 is a sectional view of one of the terminal posts. Figs. 20 and 21 are top views of two embodiments of my contact member. Figs. 22 and 23 show respectively a top view and a side elevation of another embodiment of my stationary contact. Figs. 24 and 25 show respectively a side elevation and a top view of a knife switch employing my improved contact members; Fig. 26 is a perspective view of a movable contact employing my contact members, and Fig. 27 is a view of the preferred embodiment of my improved contact member.

While I herein show my improvements embodied in a rotary snap-switch it is to be understood that some of the improvements may be adapted for other types of circuit-controlling devices.

Referring more particularly to the drawings A indicates a base or support made of porcelain or other suitable insulating material. Journalized in the base, preferably centrally thereof, is a spindle G^a which operates the switch blade or movable contact G.

Mounting switch blade.—Turning about the spindle G^a as an axis is what may be termed a movable contact carrier H which is formed preferably of sheet metal bent at its ends upon itself to form reinforcing portions. These reinforcing portions are

strengthened by tongues H^2 struck up from the carrier adjacent the reinforcing portions and at their ends engaging the latter to prevent lateral displacement of the insulation. The movable carrier is perforated through its reinforced ends to provide pockets for insulators 1. This insulating material is preferably in the form of a series of superimposed thin mica disks held 5 against axial movement in the pockets by inwardly extending annular fins, which project between the disks. These insulators support posts 2, which, at their lower ends are reduced and extend centrally through 10 the insulators, having their lower ends flattened against washers arranged at the bottom of the insulators. It will be apparent that these reduced ends not only serve for anchoring the blade posts but 15 serve to hold the disks tightly to the fins. Further it will be noted that insulators of but one size are required and minute fitting is dispensed with. The posts preferably have sliding interlocking connection with 20 the switch blade G. For this purpose each post is provided with a reduced upper end having a shoulder or head on one side thereof so as to provide a seat for the switch blade on one side of the post, the seats on 25 the two posts being disposed in the same direction. The switch blade is provided with a central opening to permit it to fit over the spindle G^3 and two longitudinal slots of a size to receive the headed exten- 30 sions of the posts. After being fitted over the headed extensions the switch blade is moved longitudinally into the seats and is held therein in any suitable manner. As 35 a means for holding the switch blade in its seats and against longitudinal movement I form a flexible lip H^3 on the upper end of one of the posts and a flexible lip G^4 on the switch blade, the lip H^3 being bent to engage one end of one of the slots and the 40 lip G^4 being bent to engage the adjacent post.

Means for moving movable contact.—As a preferred means for moving the movable contact there is secured to the spindle G^3 a 45 collar F to which one end of a coil spring or yielding actuating means J is anchored. The other end of the spring engages an upward extension M' upon a detent or latch L. This latch is arranged between two cam 50 members or rings L' and L² rigidly secured to the spindle G^3 in any suitable manner. The detent carries a depending projection L³ which extends through a slot L⁴ in the blade carrier H, to form a connection be- 55 tween the blade and a stop carrier D, and alternately engages "on" and "off" stop 60 D⁶ and D' on the stop carrier D.

The above described contact moving means is substantially that described in my 65 Patent No. 835,074 dated the 6th day of

November, 1906. In this construction and others of a like character, the stop carrier D is rigidly secured to the base or support A by depending lugs D² which project into pockets in the base or support A. Owing to 70 the fact that these lugs D² do not properly fit the walls of the pockets, the sudden jars to which they are subjected, due to the detent L³ engaging the stops D⁶ and D', will in time cause the cracking or breaking of 75 the base A. To obviate this difficulty I form the lugs D² so that they will be yielding, as for instance by splitting them longitudinally. In addition to this these lugs or anchors yield when the parts are assembled so that they bear equally on the base notwithstanding any inequalities or imperfections in the latter. Near their lower ends the lugs are provided on opposite sides with rounded noses D³ which thus form a rock- 80 ing engagement with the walls of the pocket.

Stationary contacts.—Arranged on the base A are opposite pairs of stationary contacts C adapted to be connected by the switch blade G. In a snap switch having a 90 knife blade as shown in Fig. 2 it is usual to employ flat spring contacts which are arranged to clasp the blade between them. When these flat contacts are fixed a certain distance apart, if the blade be slightly 95 thinner than desired, only the forward ends of the contacts engage the blade, or, if the blade be slightly thicker than desired, only the rear ends of the spring contacts engage the knife blade. In either case, the other 100 portions of the contacts will flare away from the knife blade. This flaring of the spring contacts from the knife blade also occurs even though the knife blade be of the proper thickness, if the fixed or stationary contacts 105 and movable contact are not held in perfect alignment in every direction; and, as switch bases of porcelain always warp from baking, even though the metal parts be minutely exact, it has been found to be impracticable 110 to carry this precision into the assembling of the metal parts on the base, that is into the finished product. With large bases and large contacts that is, large carrying capacities, these difficulties are increased. To 115 overcome these difficulties I have devised a yielding contact member having its rubbing contact portion supported preferably midway of the said rubbing surface so as to move as upon a central elastic support and to deliver a preferably equal stress at opposite extremities of the rubbing contact surface—that is the yielding contact member comprises contacting arms united by a flexing connection, the flexing axis of which lies 120 in a plane which is transverse in reference to the arms while the rubbing contact portion extends to both sides of such plane. In one embodiment of my invention as shown in Figs. 2 and 27 the contact member C is 125

formed from sheet metal, the metal being split or cut to provide a tongue, yielding side pieces, and a transverse securing portion. The tongue and the side pieces are bent as shown in Figs. 2 and —27— to provide a contact portion flexibly supported at one side thereof. The rubbing contact surface is provided with a series of holes which may extend completely through the contact portion or may extend partially therethrough, both of which are shown in Fig. 27. These holes contain graphite or other lubricant and serve to prevent the wear or cutting of the knife blade or other contact, by reason of the fact that any small particles will enter the holes and not travel back and forth over the rubbing contact surface. Of course when the holes are exposed the particles will fall out. The surface of the contact portion C opposite the rubbing surface thereof is of irregular formation being provided with ribs or serrations. These ribs or serrations are formed during the manufacture of the contact and are the result of stamping the metal with a sharp tool to form the rubbing contact surface in a plane. I have ascertained that it is necessary to form this irregular outer surface to obtain a perfectly true inner rubbing surface. I have further ascertained that this irregular surface has an advantage in that it increases the surface of the contact.

Securing contact members.—Two of the contact members C Fig. 27 are fitted around a terminal post C² with their rubbing contact surfaces opposed, the securing portion of each contact member being introduced into a transverse groove g in the rear face of the terminal post C². A wedge key C' (see Figs. 2 and 17) has its wedge portion inserted between the securing portions of the two contact members, thus securing the contact members to the rear only of the terminal post. This wedge key forms a means for forcing the forward ends of the contact member toward each other. At its rear the key is provided with upper and lower shoulders which engage the securing portions of the two contact members and hold said members in the groove in the rear of the post. The wedge key also carries a means for holding itself to the post, said means comprising two flexible arms c which are arranged on opposite sides of the post and the free ends of which are forced into recesses g¹ on the front face of the terminal post C² (see Figs. 2, 16 and 17). This form of contact may be varied in many ways. In Figs. 22 and 23, the contact members C¹⁰ are each formed from a sheet or strip of metal which is cut to provide a securing portion, guiding portions, yielding portions looped to provide flexing supports near one end, and a contact portion supported from said pivot portion at one edge.

While the contact portion is flexibly supported near one edge it is also fulcrumed intermediate its ends by guides C⁸ which extends laterally from the contact portion and works in an opening in the guide portion of the contact. 70

In Figs. 24 and 25 an ordinary knife switch is illustrated with my improved contacts. In this embodiment A⁹ indicates the base, B the contact members between which the knife blade is pivoted, and B' the contact to which the knife blade is adapted to be moved. The pocketed rubbing-contact surface has a special advantage in this embodiment, as it saves the knife blade adjacent to its pivot. 80

The contact may also be adapted for a movable contact as shown in Fig. 26. B⁸ is a movable contact carrier carrying the contacts C⁹ which are arranged vertically and are provided with curved extensions to guide the movable contacts over the stationary contacts. 85

The embodiment of my contact member C¹¹ shown in Fig. 20 is also formed, without bending, from sheet metal and comprises a securing portion, two spring arms, and a contact portion connecting the spring arms, each arm having extending therefrom guiding lugs for the movable contact. In this embodiment the contact portion is secured at one end only and lies in the plane of the spring arms and the securing portion, being provided on its inner face with the lubricant pockets and on its outer face with the radiating ribs. 95

In Fig. 21 the contact member C¹² is the same as that shown in Fig. 20 except that the contact portion is connected to the spring arms intermediate its ends, and that the guiding lugs extend from the outer end of the contact portion. It will be noted that by this arrangement the contact portion is fulcrumed intermediate of its ends. 105

Terminal post.—I provide a base plate 110 with a central struck-up hollow boss preferably of cylindrical formation (see Fig. 19) and in this boss I fit the reduced cylindrical end of the post. These parts are then secured together in any suitable manner, as for instance, by flaring the lower end of the post against the inner wall of the boss or by compressing the upper end of the boss into an annular groove in the post, or both of these. 115 120

The switch parts are inclosed by a metallic cover N lined in the usual manner with insulating material. The cover is held tightly to the base by an operating handle E which is secured to the spindle G³. 125

Construction of operating handle.—It is common to secure the operating handle to the spindle by a yielding means so that the handle will fit tightly against the cover and one of the features of this invention is the 130

provision of improved means of mounting the yielding means in the handle.

The handle is molded as shown in Fig. 10 with a central bore and two vertical grooves leading into the bore. While the handle is in a partially viscous state, a plate E³ is introduced into the two grooves. The side edges of this plate are provided with teeth or serrations which are disposed in such a direction that they will easily slide into the handle, but cannot be withdrawn without carrying pieces of the handle out with them when the handle is in a viscous state, or without breaking the handle when the handle is hardened. The plate E³ (see Fig. 11) is provided with a central spring opening and integral spring seats at the bottom of the opening. In the opening with its lower end resting on the seats is positioned a helical spring E⁵ which bears at its upper end against a plate E⁶ (Fig. 12) carried by the upper end of a nut E⁴, (Fig. 13) the plate being recessed at diametric points so as to be guided on the side walls of the spring opening in plate E³. The upper end of the nut E⁴ (see Fig. 13) is provided with a pocket to receive a depending guide T integral with plate E³, while the lower end is enlarged and is provided with grooves in which work the walls of a throat leading from the bottom of the spring opening in the plate E³. The nut E⁴ is adapted to engage the threaded upper end of the spindle G³. When the parts of the handle have been assembled, as shown in Fig. 2, and the handle has been applied to the spindle G³, an inclined lug E² on the plate E³ enters into a notch on the ring F before mentioned and positively positions the handle, and its carried parts, relatively to the switch blade in a manner described in my patent before mentioned.

Indicating means.—It is a common practice to secure the movable member of an indicating means to the snap actuated portions of circuit controlling devices but this securing means has added greatly to the cost of the device. As my operating handle is positively positioned relatively to the switch blade, I am enabled to secure the movable indicating means directly to the handle. To accomplish this I provide, in one embodiment, an indicating disk G⁵ (see Fig. 3) with a central elongated opening corresponding in shape and size to a horizontal section through the operating handle E. The disk is then fitted over the handle and rests upon an annular flange which is on the bottom of the handle, this flange closing the opening in the cover through which the positioning means E² projects as shown in Fig. 2. To hold the disk to the handle, the disk is provided with two tongues which are cut from the metal of the disk G⁵ at opposite ends of

the opening therein and are bent beneath the ends of the operating handle. When the disk G⁵ is being fitted to the handle the tongues are depressed so as not to project into the path of the handle. The handle being non-circular or elongated in cross section and fitting in a similar opening in the disk prevents the turning of the disk relatively thereto while the tongues prevent upward displacement of the disk. The indicating characters G⁶ have usually been painted on the switch. These characters in time wear off or become coated with dirt thus destroying their indicating quality. Further they are not visible at night or when the switch is installed in a dark place. To overcome these difficulties I cut away the disk to form the characters and position beneath the cut away portion a sheet of mica treated on both faces with a luminous material.

It is common to provide the indicating disk with a guard which covers or hides from view all but the word or character indicating the condition of the circuit. This guard forms the stationary member of the indicating means. These guards are so constructed that they throw a shadow over the indicating word or character. This difficulty I overcome by providing a guard N² which has a width approximately equal to the height of the characters, and is supported over the characters by a peripheral flange which engages the periphery of the cover N. The guard is cut away to expose the characters that are to indicate the position of the switch. It will be noted that by reason of the segmental ring shape of the guard it will be spaced from the center of the top of the switch, thus admitting light from all directions to the characters. The guard is secured against accidental displacement by bosses or projections on the cover engaging in openings or recesses in the flange of the guard as shown in detail Fig. 8.

To permit the indicator G⁵ to be removed without removing the guard, I provide the indicator with a radial slit or slot 10 which terminates at its inner end in a lateral slit or slot 11, while the end of the guard upon the right hand of the cut away portion is bent or flared away from the indicating disk G⁵ and the end on the left side of said cut away portion is bent toward the disk and may contact with the latter. When the operating handle E³ is turned to operate the device the slit in the disk will pass both ends of the guard, but when the operating handle is rotated in the opposite direction to remove said handle, the inwardly turned end of the guard will move into the slot and the disk will ride over the guard and from beneath the same. Thus it will be seen that I provide a means

for removing the indicating disk without removing the guard.

In Figs. 4, 5 and 6 I have shown an indicating means wherein the indicating characters are stationary, being carried by the cover N° which forms the stationary member of the indicating means, the cover being provided with an annular elevated portion in which the indicating characters are 10 pierced. Beneath the pierced characters and between the cover and its insulating lining are arranged mica plates which are, as in the other embodiment, coated on both faces with a luminous material. The guard 15 N° is in the form of a ring having a depending flange which is fitted to the periphery of the cover, the elevated character-carrying portion of the cover being but slightly below the top of the ring so as not 20 to be shaded by the guard. The movable member of the indicating means is in the form of a rotary shutter G° which at its ends is bent beneath the guard N°. This shutter is provided at its center with a non- 25 circular opening which fits a noncircular boss on the top of a washer E°, the washer being provided in its periphery with pockets having recesses at their lower ends. Into these pockets are fitted tongues depending 30 from the shutter, said tongues having their extreme ends forced into the recesses at the lower ends of the pockets to hold the shutter on the washer. The washer rests on the center of the cover and over the spindle 35 opening in the latter, being thus surrounded by the elevated character-carrying portion of the cover. To hold the washer and consequently the shutter to the cover so that they will not become separated, the washer 40 is provided with an annular rib or flange at its bottom and over this flange are bent lips or tongues N° struck up from the cover N. Surmounting the washer E° is the handle E° which has the usual screw threaded 45 connection with the spindle and which is provided with a depending lug which enters a notch in the top of the washer. It is apparent that by simply removing the handle from its spindle the cover with its indicating 50 means may be removed, thus obviating the handling of a great number of parts when inspecting the switch.

I claim:—

1. In a circuit controlling device, a support, coöperating contact elements carried thereby, at least one of said elements comprising conducting arms, a rubbing contact portion, and a flexing connection between the said arms and rubbing portion, the flexing axis of which connection lies in a plane which is transverse with reference to the arms, the said rubbing contact portion extending to both sides of the said plane.

2. In a circuit controlling device, a support, coöperating contact elements carried

thereby, at least one of said elements having a portion returned upon itself, and a rubbing portion extending in an opposite direction from the said return portion.

3. In a circuit controlling device, a support and an electrical contact carried thereby, a movable contact member coöperating with the first named contact, actuating means for the movable contact member including a movable part having a plurality of 70 pockets and integral fins projecting into the pockets, insulators seated in said pocket and held in place by said fins, and connections between the insulators and movable contact member for transmitting motion to the 80 latter.

4. In a circuit controlling device, a support and an electrical contact carried thereby, a movable contact member coöperating with the first named contact, actuating 85 means for the movable contact member including a movable part provided with a plurality of pockets and integral fins projecting into the pockets, laminated insulators seated in the pockets and held in place by said fins, 90 and connections between the insulators and movable contact member and binding the laminae of said insulators together.

5. In a circuit-controlling device, a support, a plurality of electrical contacts carried thereby, a movable contact adapted to connect said electrical contacts, means for operating the movable contact, a detent for controlling said operating means, and a detent stop carrier for the detent, provided 100 with yielding anchoring means.

6. In a circuit-controlling device, a support, a plurality of electrical contacts carried thereby, a movable contact adapted to connect said electrical contacts, means for 105 operating the movable contact, a detent for controlling said operating means, and a detent stop carrier for the detent, having lugs split longitudinally and connected to the support.

7. In a circuit-controlling device, a support, a plurality of electrical contacts carried thereby, a movable contact adapted to connect said electrical contacts, means for operating the movable contact, a detent for controlling said operating means, and a detent stop carrier for the detent having anchoring lugs connected to the support and having rocking bearing surfaces on at least 115 one side.

8. In a circuit-controlling device, a support, a plurality of electrical contacts carried thereby, a movable contact adapted to connect said electrical contacts, means for operating the movable contact, a detent for controlling said operating means, a detent-stop for the detent, and a yielding connection between the detent stop and the support.

9. In a circuit-controlling device, a sup- 130

port, a movable contact on the support, and a stationary contact also on a support comprising a terminal post, a pair of contact members loosely fitted on the post, and a 5 fastening means including a wedge to spread and hold the members on the post.

10. In a circuit-controlling device, a support, a movable contact on the support, a terminal post, a pair of contact members 10 loosely mounted on the post, and a fastener including a wedge arranged between and spreading the ends of the members apart.

11. In a circuit controlling device, a support, a movable contact, a terminal post, a 15 pair of contact members mounted upon the post, and means for forcing the contact portions of said contact members toward each other.

12. In a circuit-controlling device, a support, a movable contact on the support, a stationary contact also on the support, comprising a terminal post, a pair of contact members, a fastener including a wedge arranged between the ends of the members, 25 and means carried by the fasteners for holding the wedge to the post.

13. In a circuit controlling device, a support, a movable contact on the support, a stationary contact also on the support comprising a terminal post, a pair of contact members, and a fastening device to hold them to the post, provided with arms 30 engaging the post.

14. In a circuit-controlling device, a support, a movable contact on the support, a stationary contact also on the support comprising a terminal post provided with a transverse groove, a pair of contact members having portions thereof seated in the groove, 40 and means arranged in the groove between the contact members to hold the contact members in the groove, and having flexible arms arranged on opposite sides of the post and engaging the front thereof.

45. 15. In a circuit-controlling device, a support, a contact carried thereby, a coöperating movable contact, a spindle connected to the movable contact, a handle for operating the spindle comprising an insulating portion, a spindle engaging member, and a plate in the insulating portion provided with a recess receiving the spindle engaging member, and having a contracted throat closely fitting the spindle engaging member, 50 and a spring in the recess engaging said throat and urging the spindle engaging member into the handle said plate having sliding interlocking connection with the spindle.

60. 16. In a circuit-controlling device, a support, a contact carried thereby, a coöperating movable contact, a spindle connected to the movable contact, a handle for operating the spindle comprising an insulating portion, a spindle engaging member, and a

plate in the insulating portion provided with a recess receiving the spindle engaging member, and having a contracted throat closely adjacent the outer end of the spindle engaging member, and means adjacent the 70 contracted throat and connected with the spindle for engaging the plate and positioning the handle relatively to the movable contact.

17. In a circuit-controlling device, a support, coöperating contacts carried thereby, and circuit indicating means for the contacts comprising a movable member and a stationary member, one of which members is provided with pierced indicating characters, and luminous means on the pierced number beneath said pierced characters for closing the same.

18. In a circuit controlling device, a support, coöperating contacts carried thereby, 85 a handle moving with one of said contacts, and an indicating means for the contacts comprising a stationary member and a movable member, the latter being provided with a non-circular opening fitting upon the 90 handle and with tongues bent into engagement with said handle.

19. In a circuit-controlling device, a support, coöperating contacts carried thereby, an operating spindle, for one of said contacts, an operating handle having a connection with said spindle said connection including means whereby the handle may be removed therefrom when rotated in one direction, an indicating member moving with 100 said handle, a guard for the indicating member, and means coacting with the moving member to remove the latter member from beneath the guard when the operating handle is moved to remove the latter from 105 the spindle.

20. In a circuit-controlling device, a support, coöperating contacts carried thereby, an indicating means for the contacts comprising a movable member and a guard, and means coacting with the movable member to remove the latter member from beneath the guard when said movable member is moved in one direction.

21. In a circuit-controlling device, a support, coöperating contacts carried thereby, a cover for the contacts, an indicating means for the contacts comprising a movable member arranged on the outside of the cover, and a guard for the movable member, and 120 means co-acting with the movable member to remove the latter member separately from the guard.

22. In a circuit-controlling device, a support, coöperating contacts carried thereby, and an indicating means comprising a movable disk having a radial slot, and a segmental guard having one end turned toward the disk and the other end turned away from the disk.

23. In a device of the character described, a support, coöperating contact elements carried thereby, at least one of which elements includes a member projecting from the said support and bearing a rubbing contact portion having a rubbing face and a reverse or rear surface, a yielding connection between the said rubbing contact portion and the said projecting member which yielding connection is adjacent the said rubbing face and extends back of a plane in which the said reverse or rear surface resides, the said rubbing portion extending from the said yielding connection both toward and from the said projecting bearing member.
24. In a device of the character described, a support, coöperating contact elements carried thereby, at least one of said elements comprising a bearing piece for a conducting arm, a conducting arm with an opening therein between the free end of the said arm and its said bearing piece, a rubbing contact portion connected to the said arm adjacent the free end thereof and adjacent the said opening, the said rubbing contact portion extending from its said connection at the free end of the arm toward the said bearing piece and extending also from the last said connection away from the said bearing piece.
25. In a device of the character described,
- a support, coöperating contacts carried thereby, one of said contacts comprising an arm having a return bend and a return part with a rubbing contact element, a portion cut 35 from the said arm bent away from the same and beyond the said return bend and into alignment with the said rubbing contact element so as to co-act with the other said co-operative contact.
26. In a device of the character described, a support, coöperating contact elements carried thereby, at least one of said elements comprising a bearing piece for a yielding conducting arm, an integral rubbing contact portion yieldingly connected to the said arm which rubbing portion has free ends projecting from the said yielding connection respectively toward and from the said bearing piece.
27. In a device of the character described, a cover, exterior movable indicating means, a guard over the said indicating means, and means for disengaging the said indicating means from the said guard by a backward 50 turning of one of the said members.

In testimony whereof I affix my signature, in presence of two witnesses.
